FIG. 3.

UNITED STATES PATENT OFFICE

2,277,820

HAT MACHINE

George W. Cuming, deceased, late of New York, N. Y., by Ella B. Cuming, executrix, Charlottetown, Prince Edward Island, Canada, assignor to M. A. Cuming & Company, Inc., New York, N. Y., a corporation of New York

Application July 2, 1940, Serial No. 343,546

3 Claims. (Cl. 223—13)

This invention relates generally to hat forming machines and more particularly to a block or die of such machine wherein differential pressure is applied to those portions of the structure shaping the crown and brim of the hat, respectively.

The primary object of this invention is a block or die in which the crown forming and brim forming members are separate entities.

Another object of the invention is to so mount crown and brim forming members as to permit differential pressures to be applied to the respective members.

A further object of the invention is to support separate crown and brim forming members odd per se on a hollow head such as shown in United States Patent No. 2,064,824.

The invention also seeks a hat forming structure suitable for use with differential pressures which is practical from the standpoint of ease of manufacture, celerity of assembly and convenience and durability in use.

These and other objects of the invention and the means for their attainment will be more apparent from the following detailed description, taken in connection with the accompanying drawing illustrating one embodiment by which the invention may be realized and in which:

Figure 1 is a view in transverse section showing a block or die of a hat forming machine to which the invention is applied;

Figure 2 shows a top view of the structure of Figure 1; and

Figure 3 is a fragmentary, transverse, sectional view taken in the plane indicated by the line 3—3 of Figure 2 and looking in the direction of the arrows.

The invention is here illustrated as applied to the upper block of a hat forming machine but it is to be understood that it is equally applicable to either the upper or the lower block or head of such machine.

As illustrated, the upper wall 5 of the hollow head 7 is formed centrally with a depending portion 9 formed with a vertical passage 11. A brim forming disc-like element 13 of flexible material such as rubber is carried on the lower edge 15 of the head by a retaining annulus 16 and is of such size and shape as to extend upwardly and be in contact with a spacing and positioning plate 17 interposed between the depending portion 9 and the brim forming element 13, an aperture 19 in the brim forming element 13 and an aperture 21 in the plate 17 registering with the passage 11. Sealing means 23 may be

disposed between portion 9 and the plate 17 and is apertured, as at 25, to register with the apertures 19 and 21.

The dome or crown forming bag element 27 which is also of yielding material, such as rubber, may take any shape, here shown as oval, and has formed integral with the upper edge of the wall an inwardly extending lip or flange portion 30 defining an oval aperture into the interior 10 of the bag 27 which is held in place by the oval disc 32 having an aperture 34 registering with the passage 11 so that the element 27 is substantially a closed body with only the aperture 34 in register with the passage 11. The inner 15 surface of this top wall 30 is provided with a continuous depending rib 36 which is received in the annular groove 38 in the plate 32 adapted to retain the parts in proper positions. As shown, the disc 32 is formed with a thicker oval portion 20 39 coinciding with the inner wall of groove 38 which fits within the opening 31 and whereof its upper surface lies flush with the top surface of the crown bag 27.

Plate 32 is held in position by bolts 40 shown 25 as diametrically disposed upon opposite sides of the passage 11 and passing through registering holes in the parts 9, 17, 13, 30 and threaded into threaded apertures in plate 32 and the heads 42 of the bolts 40 being accessible from without 30 the head 5.

Fluid, either liquid or gaseous, enters the space 35 between the brim forming element 13 and the dome 5 from one source (pipe 46) and enters the crown member 27 through the pipe 46 entering passage 11.

The hat die of this invention is readily assembled and disassembled. By the removal of the two bolts 40, the plate 32 is released, thereby 40 also releasing the crown bag 27 for removal. The plate 32 may then be removed from the crown bag by passing it endwise through the opening 31. The brim forming member 13 is released by removing annulus 16 as by removing the bolts 48. This permits access to the spacing 45 plate 17 and gasket 23.

Various modifications will occur to those skilled 50 in the art in the composition, configuration and disposition of the component elements going to make up the invention as a whole as well as in the selection and combination of particular features to accomplish specific results, and no limitation is intended by the phraseology of the foregoing description or illustrations in the accompanying drawing except as indicated in the appended claims.

What is claimed is:

1. In a hat machine, in combination, a head member having a fluid depending central portion formed with a passage and bolt holes on opposite sides of the passage, a disc-like brim forming element of yielding non-metallic material formed with an aperture to register with the passage in the head and bolt holes to register with the holes in the head, means to secure the periphery of the brim forming element to the head, a plate between the brim forming element and the head and formed with an aperture to register with the passage in the head and bolt holes to register with the bolt holes in the head, sealing means between the plate and the depending portion of the head, a separate crown bag formed with an inwardly directed lip, said lip being formed with a continuous bead on its surface, a retaining plate within the crown bag formed with a continuous groove in its upper surface to receive the bead on the crown bag and threaded apertures to register with the aforesaid bolt holes and an aperture therebetween to register with the passage and bolts in the bolt holes.

2. In a hat machine, the combination with a

head member formed with a fluid passage, of a brim forming element formed with a fluid aperture to register with the fluid passage in the head, a separate crown bag formed with an inwardly directed lip, said lip being formed with a continuous bead on its lower surface, a retaining plate within the crown bag formed with a continuous groove in its upper surface to receive the bead on the crown bag and an aperture to register with the passage and means to retain the retaining plate in position.

3. In a hat machine, the combination with a head, of a brim forming element, a separate crown bag formed with an inwardly directed lip, said lip being formed with a continuous bead on its lower surface and a retaining plate within the crown bag formed with a continuous groove in its upper surface to receive the bead on the crown bag, that portion of the plate within the groove being of increased thickness to be received within the aperture defined by the lip.

ELLA B. CUMING,
*Executrix of the Estate of George W. Cuming,
Deceased.*

CERTIFICATE OF CORRECTION.

Patent No. 2,277,820.

March 31, 1942.

GEORGE W. CUMING, DECEASED,
BY ELLA B. CUMING, EXECUTRIX.

It is hereby certified that error appears in the printed specification of the above numbered patent requiring correction as follows: Page 2, first column, line 3, claim 1, strike out "fluid" and insert the same before "passage" in line 4, same claim; and that the said Letters Patent should be read with this correction therein that the same may conform to the record of the case in the Patent Office.

Signed and sealed this 23rd day of June, A. D. 1942.

(Seal)

Henry Van Arsdale,
Acting Commissioner of Patents.
